Primary Examiner — Maria J. Edwards(74) *Attorney, Agent, or Firm* — Suzanne Kikel, Patent Agent(57) **CLAIM**

The ornamental design for a sleeve for a handle, as shown and described.

DESCRIPTION

FIG. 1 is a front perspective view of a sleeve for a handle, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof in an operative mode wrapped around a handle.

The broken lines illustrate environmental structure and form no part of the claimed design.
